UNITED STATES PATENT OFFICE.

FRANK A. ALLINGER, OF LOS ANGELES, CALIFORNIA, ASSIGNOR OF ONE-HALF TO
CHRIST VOLZ, OF LOS ANGELES, CALIFORNIA.

LOCOMOTIVE FIRE-BOX.

1,165,932.

Specification of Letters Patent. Patented Dec. 28, 1915.

Application filed August 5, 1914. Serial No. 855,126.

To all whom it may concern:

Be it known that I, FRANK A. ALLINGER, a citizen of the United States, residing at Los Angeles, in the county of Los Angeles and State of California, have invented a new and useful Locomotive Fire-Box, of which the following is a specification.

This invention relates to air supply pans for oil burning engines.

10 The object in general of the invention is to provide an air supply pan for an oil burning engine with means for heating the air thoroughly before it enters the engine fire box and for distributing the air uniformly 15 within the fire box, thus insuring a more thorough mixture of the air with the oil fuel constituents and a more uniform and complete combustion of said mixture, in the engine fire box than can be attained in the 20 oil burning engines now in use.

Other objects will appear hereinafter.

Referring to the drawings: Figure 1 is a longitudinal section of an engine boiler, fire box and air supply pan, the air supply pan being shown in the form of my invention. Fig. 2 is an enlarged transverse vertical section of my improved air supply pan taken on line x^2-x^2 of Fig. 1. Fig. 3 is a detached plan view of my improved air supply pan. Fig. 4 is an enlarged plan view of one of the air supply pan lining bricks. Fig. 5 is an enlarged side view of said brick.

My improved air supply pan is particularly adapted for use on oil burning locomotives and in the drawing are shown a locomotive boiler 1 and fire box 2, to the bottom of which fire box my improved air supply pan is attached in the manner hereinafter described. My improved air supply pan 40 comprises an upper receptacle 3 and an air chamber 4, located directly below said receptacle; said chamber having an air inlet 5. The walls of said chamber and receptacle are so arranged as to form air spaces 7 therebetween, for the diffusion of the air in the air chamber, which is controlled by door 6. The wall 8, of receptacle 3 is inclined slightly and is provided with a plurality of perforations 9, which provide communication from the air spaces 7 to said receptacle. The air supply pan has flanges 10, provided with holes 11 through which bolts 12 are inserted and screwed into the lower extremities 13 of the walls of the fire box 2, for attaching the air supply pan in position directly

below the fire box. The receptacle 3 is lined with fire brick 20 and 21, which may be laid with their wide sides against the wall 8 inasmuch as said wall is inclined only slightly. The fire brick 20 are provided with perforations 22 and rest over the perforated portion of the receptacle wall 8 while the brick 21 are the ordinary plain fire brick. The fire brick 20 are provided with grooves 25 in their lower faces which grooves provide communication between the perforations 9 in the receptacle wall 8 and the perforations 22 in said brick. Through the forward wall of the air supply pan receptacle 3 projects an oil fuel nozzle 30.

It will be noted that the air supply pan is of considerably less length than the receptacle 3 and that the former extends under the latter and entirely across the same adjacent the rear end thereof. The walls of the receptacle are only perforated over the air supply pan and therefore the air entering the receptacle through these openings does not come into contact with the fuel entering through the nozzle 30 until said fuel has had a chance to move some little distance away from the forward end wall of the receptacle. This is an important feature since it prevents the intense heat of combustion playing directly against the fire brick at the rear end of the receptacle. It is also desired to call attention to the fact that the fuel when it enters the receptacle 3 is traveling in an opposite direction to the air coming through the perforations 22 and moving toward the fire tubes and therefore a thorough mixture of the two constituents takes place.

The operation is as follows: Air is admitted into the chamber 4 upon opening the door 6 which allows the air to flow into the chamber through inlet 5. From the air chamber 4 the air flows through the perforations 9 in the receptacle wall 8 into the grooves 25 of the fire brick 20, through the perforations 22 in said fire brick, and into the air supply pan receptacle 3. Oil fuel is injected into the receptacle 3 through nozzle 30 in the usual manner and when the oil has united with the air in the receptacle, it is ignited in the fire box and heat thereof heats the water in the engine boiler 1 in the usual manner for the production of steam.

The circulation of the air through air spaces 7, perforations 9, in receptacle wall

8, grooves 25, and perforations 22, in fire brick 20, diffuses the air considerably and the heat of the fire brick 20 causes the air to be heated as it passes through the fire brick, before it is mixed with the oil fuel and ignited. The diffusion and heating of the air enable the air to mix readily and thoroughly with the oil fuel constituents, which is conducive to the highest efficiency in complete combustion of the oil fuel and in the generation of heat of the highest intensity. The complete combustion of the oil fuel moreover, effects a considerable saving in the amount of fuel used per unit of work, and does not allow the formation of carbon and the deposit of soot in the fire box and air supply pan.

What I claim is:

1. An air supply pan for engine fire boxes 20 having a pair of slightly inclined downwardly converging walls, an air chamber formed under said receptacle adjacent the rear end thereof and extending entirely across the receptacle, said air chamber having downwardly converging side walls, said side walls being connected at their upper edges to the bottom of the receptacle and diverging from the walls of the receptacle, the walls of the receptacle being perforated 25 above the air chamber and being imperforate in advance of the air chamber, means for admitting air to the air chamber, means for

ejecting fuel into the receptacle and fire brick covering the walls of the receptacle, said fire brick being formed with perforations communicating with the perforations formed in the rear end of the walls of the receptacle. 35

2. An air supply pan of the character described, comprising a receptacle having 40 slightly inclined downwardly converging side walls, an air chamber under said receptacle and having downwardly converging side walls connected along their upper edges to the side walls of the receptacle near their 45 outer edges, those portions of the walls of the receptacle which extend over the air chamber being perforated, perforated fire brick covering the perforated portions of the walls of the receptacle, said fire brick 50 being provided with channels which establish communication between the perforations in the walls of the receptacle and the fire brick perforations, means for admitting air into the air chamber, and means for injecting fuel for combustion into said receptacle. 55

In testimony whereof, I have hereunto set my hand at Los Angeles, California, this 31st day of July, 1914.

FRANK A. ALLINGER.
